INVENTOR
David H. McCray
ATTORNEY

UNITED STATES PATENT OFFICE.

DAVID H. McCRAY, OF TULSA, OKLAHOMA.

OIL-WELL JACK.

Application filed March 17, 1924. Serial No. 699,667.

To all whom it may concern:

Be it known that I, DAVID H. McCRAY, a citizen of the United States, residing at Tulsa, in the county of Tulsa and State of Oklahoma, have invented certain new and useful Improvements in Oil-Well Jacks; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to oil well jacks known in the oil field nomenclature as "Barrett" jacks and it conforms generically to the general construction shown in the patent to J. Barrett, No. 527,102, patented October 20, 1894. Such jacks are extensively used in the oil fields for screwing and unscrewing or jointing and disjointing tools used in oil well drilling in the so-called standard or reciprocatory drilling method.

25 In actual practice it has been found that while the so-called "Barrett" jack is a very efficient apparatus for jointing the tools and the like, difficulty is experienced in disjointing or unscrewing. The generally accepted reason for this is that the tools become stuck or frozen during the drilling operation and inasmuch as the full power of the jack is used for screwing up the tools, there is no reserve power left for unscrewing them.

35 In other words, the power required to unscrew the tools is the power used for screwing them together plus the power required to overcome the frictional resistance or tendency to stick.

40 The problem then is not merely to provide a jack of great power but in order to have the jack operate successfully, it must have a disjointing power in excess of the jointing power so I have provided means for varying the power by providing a fulcrum for the socket lever which will be adequate to join the tools and in addition I have provided means for varying the fulcrum of the socket lever so that the fulcrum will cause a greater multiplication of the applied power for unscrewing or disjointing them than will be applied for joining or screwing the tool sections.

55 The novel manner in which the desired result is obtained will be apparent by ref-

erence to the following description in connection with the accompanying drawings, in which—

Fig. 1 is a perspective view of a jack constructed in accordance with my invention. 60

Fig. 2 is a cross sectional view through the traveler showing the power applying mechanism in elevation, part of the socket lever being shown in section.

Fig. 3 is a disassociated perspective view 65 of the fulcrum and the locking lever.

Fig. 4 is a perspective view of the clip for the locking lever.

Fig. 5 is a detail view of one end of the socket lever and the power-applying disk 70 with the fulcrum in one position.

Fig. 6 is a similar view with the fulcrum in another position, and

Fig. 7 is a detail perspective view of one 75 end of the traveler, showing the wrench-receiving seat and the fulcrum seats.

1 designates a rack, 2 the wrench post and 3 the traveler or traveling carriage provided with the wrench socket 4. The traveling carriage has two pawls or dogs 5 and 6 to engage the rack teeth 7. These dogs or pawls are connected to the reversing lever 8 by the links 9 and 10, the reversing lever being controlled by a trip lever 11.

All of this mechanism is old and well 80 known but instead of connecting the dogs to the socket lever as is the usual practice, I connect them to a rocking actuator 12 in the form of a geared disk. The actuator 12 has a portion of its periphery provided with 90 teeth 13, which mesh with teeth 14 on the end of the socket lever 15.

The socket lever is mounted on a variable fulcrum 16 which constitutes the important part of my invention. The fulcrum 16 consists of a transverse rod having flat faces 17 and 18 so that the rod 16 is of less width across the flat faces than the narrow portion 19 of the slot 20 in the socket lever 15. The slot 20 has two substantially circular portions 21 and 22, which constitute bearings resting on the journal or fulcrum 16, the edges of which are round, as at 23 and 24.

The slot 20 corresponds to similar slots 105 25 and 26 in the sides of the traveler or carriage 3 so that the fulcrum journal 16 may be turned in the position shown in Fig. 5 to move it from one end of the slots 20, 25 and 26 to vary the fulcrum of the 110

result is obtained will be apparent by ref-

socket lever 15, it being obvious that when the journal 16 is in the rounded portion 22 of the slot 20 and in the lower portions of the slots 25 and 26, greater power will be exerted upon the actuator 12 than when it is in the portion 21 of the slot 20 and the upper portions of the slots 25 and 26.

It will be observed that the journal 16 has a collar 27 at one end which bears 10 against the side wall of the hollow carriage or carrier 3. The opposite end of the journal or fulcrum 16 is provided with a constricted portion 28, projecting through the side 29 of the carriage and it is also 15 provided with an opening 30 through which a bolt 31 may pass to fasten the bifurcated end 32 of the locking lever 33 to the fulcrum, the bolt being provided with the usual nut 34.

20 The locking lever 33 extends on the outside of the carriage or carrier and it is adapted to be held against swinging movement by the U-shaped spring clip 35, which is secured to the side of the carriage 3.

25 If the device is being used for screwing up the tools or joining them, the member 16 will be in the position shown in Fig. 6. Ample power will be provided for rocking the actuator 12 so that the dogs can perform in the usual way. When it is desired to unscrew or disjoint the tools, the handle 33 will be disengaged from the clip 35 and the parallel flat sides 17 and 18 of the members 16 will be turned 30 at right angles to the position shown in Fig. 6 so that the fulcrum can be moved to the position shown in Fig. 5. Then the handle is swung back to cause the parallel flat sides 17 and 18 to assume substantially the positions shown in Fig. 6, 35 but by this time the fulcrum will be in the portion 22 of the slot 20. Since the fulcrum will be nearer the toe or lower end of the socket lever 15 than when the fulcrum is in the portion 21 of the slot 20, it will be apparent that the same amount of power applied to the socket lever will exert a greater force on the wrenches, quite enough to make up the difference between 40 the amount of power applied in screwing up the tools plus the tendency of the parts to adhere so that the jointed connections can be broken away one from the other with a device having more power than the device which screwed them together.

55 This is quite an important feature since actual practice has demonstrated that in the oil fields one weakness of the so-called "Barrett" jack is that while it is quite efficient and rapid in joining the tools, greater difficulty is experienced in disjoining them and as above pointed out, the generally accepted explanation is that the jack cannot exert sufficient power to break the joint or disconnect the tools after they have been

screwed together and used. Therefore, the importance of varying the fulcrum for the socket lever will at once become apparent.

What I claim and desire to secure by Letters Patent is:

70

1. In an oil well jack including a rack, a carriage, a mechanism for propelling the carriage over the rack, an actuator for the propelling mechanism including a geared member, a socket lever or actuating geared member, and a variable fulcrum for the socket lever adjustably mounted in the carriage.

75

2. In an oil well jack including a rack, a carriage, a mechanism for propelling the carriage over the rack, an actuator for the propelling mechanism including a geared member, a socket lever or actuating geared member, and a variable fulcrum for the socket lever adjustably mounted in the carriage, the fulcrum consisting of a member longitudinally movable with respect to the socket lever.

80

3. An oil well jack comprising a rack, a traveling carriage on the rack for actuating a wrench, a pivoted disk in the carriage, dogs actuated by the disk for intermittently engaging the rack, a dog reversing mechanism carried by the carriage, a socket lever having an elongated slot with a constricted intermediate portion, and a fulcrum journal movable through the constricted portion of the slot to either end thereof, the journal being mounted in slots in the sides of the carriage similar to the slots in the socket lever.

90

4. An oil well jack comprising a rack, a traveling carriage on the rack for actuating a wrench, a pivoted disk in the carriage, dogs actuated by the disk for intermittently engaging the rack, a dog reversing mechanism carried by the carriage, a socket lever having an elongated slot with a constricted intermediate portion, a fulcrum journal movable through the constricted portion of the slot to either end thereof, the journal being mounted in slots in the sides of the carriage similar to the slots in the socket lever, and a locking lever on one end of the journal outside the carriage for manipulating it from one end of each slot to the opposite end thereof.

105

5. An oil well jack comprising a rack, a traveling carriage on the rack for actuating a wrench, a pivoted disk in the carriage, dogs actuated by the disk for intermittently engaging the rack, a dog-reversing mechanism carried by the carriage, a socket lever having an elongated slot with a constricted intermediate portion, a fulcrum journal movable through the constricted portion of the slot to either end thereof, the journal being mounted in slots in the sides of the carriage similar to the slots in the socket lever, and a locking lever on one end of the

110

115

120

125

130

journal outside the carriage for manipulating it from one end of each slot to the opposite end thereof, said locking lever being pivoted to the journal.

- 5 6. An oil well jack comprising a rack, a traveling carriage on the rack for actuating a wrench, a pivoted disk in the carriage, dogs actuated by the disk for intermittently engaging the rack, a dog-reversing mechanism carried by the carriage, a socket lever having an elongated slot with a constricted intermediate portion, a fulcrum journal movable through the constricted portion of
- 10

the slot to either end thereof, the journal being mounted in slots in the sides of the carriage similar to the slots in the socket lever, a locking lever on one end of the journal outside the carriage for manipulating it from one end of each slot to the opposite end thereof, said locking lever being pivoted to the journal, and a clip on the side of the carriage for holding the locking lever in normal position.

In testimony whereof I affix my signature.

DAVID H. McCRAY.
